AUTOMATIC SELF-INDEXING
COMMUTATOR SLOTTER

Irving Spector, Miami, Fla.

Application October 16, 1947, Serial No. 780,248

9 Claims. (Cl. 90—15.1)

1

This invention relates to an automatic self-indexing commutator slotted.

An object of the invention is to eliminate the necessity of manually operating a cutting head or adjusting and aligning the mica segments to the cutter wheel, or removing the armature and placing it in a separate machine for the purpose of slotting.

Another object of the invention is the incorporation of means whereby the mechanism may be folded back and locked out of the way so that the lathe may be used unobstructed for other turnings.

A still further object of the invention is the production of an efficient mechanism comprising mechanical and electrical means, depending on whether the armature has been turned perfectly smooth, with the mica flush, or if the grooves are still present and only need cleaning up, adjustments being provided for either condition; the mechanism also shuts off automatically at the completion of the slotting, when used with the electrical indexing method.

With the foregoing and other objects in view, my invention comprises certain novel constructions, combinations, and arrangements of parts as will be hereinafter fully described, illustrated in the accompanying drawings, and more particularly pointed out in the appended claims.

In the drawings:

Fig. 1 is a view in front elevation of a mechanism constructed in accordance with the present invention, including an armature mounted in a lathe as in turning, and the slotting attachment bolted to the rear of the lathe carriage and permanently aligned laterally with the lathe centers, while

Fig. 2 is a similar view with some of the elements shown in section, and some elements shown moved to the right from the position shown in Fig. 1.

Fig. 3 is a side view, in elevation, showing some of the elements in vertical section.

Fig. 4 is an enlarged fragmentary view in elevation, of the mechanism shown in Fig. 3.

Referring to the drawings, in which the preferred embodiment of the invention is illustrated, 1 designates a motor of $1/12-1/20$ H. P., and 2 is a cam driven by said motor through a double reduction worm drive 3 mounted in a housing 3'. An extension of this housing 4 carries the cutting arbor 5; said arbor 5 has a threaded spindle 6 on the outer end of which is slotting milling wheel 7.

A flat mounting bed 8 is provided with at-

2

tached eye fittings 9 and 10, enabling the assembly to slide upon the shafts 11 and 12.

A reciprocating movement is obtained by the thrust of the cam wheel 2 against the stationary roller-member 13. The cam shaft 14 and the cam 2 are not attached to each other, but are of floating construction, the coupling being through a pin 15 and driving-arm 16. This arrangement permits the positive drive to be applied to the sliding carriage assembly to the left, which is the cutting stroke, and a comparatively speedier return action to the right motivated by the loading spring 17. A dash-pot 18 is attached to the fitting 9 as shown. The function of the loose-coupled cam 2 will be herein-after more fully explained.

The second major sub-assembly of the mechanism consists of the following: A brush 19 makes electrical contact with the projecting rim 20 of the commutator 21, and is slideably attached to brush-holder 22, by means of the retaining screws 23 in the slotted portion 24 of the brush 19 and held in contact with the spring 25, and a mounting-bar 26 which is affixed at its upper end to shaft 11. A second brush 26 makes contact with the commutator body 27 (see Fig. 3), and has a slotted holder 28 slidably fixed to its mounting-bar 29 (see Fig. 3), by means of screws 30 and 31 in their respective slots 32 and 33, so that the cam 34 will lift said holder 28 as the sliding carriage assembly passes under the roller 35 carried by said holder. The mounting-bar 29 and holder 28 are slotted at their lower ends to permit a sliding-plate 36 to project through them, and allow the vertically acting holder 28 to be raised and lowered by the said cam 34. The mounting-bar 29 is adjustable with respect to the commutator's length by means of the threaded shaft 37 having a grip 38 at one end and held in the bar 29 by the set collar 39. The bar 29 is guided by the rods 40 and 41 which pass through the member 21. (See Figs. 1 and 2.) A shaft 42 is attached to the upper portion of the bar 29 and the end of said shaft 42 carries a stopping block 43 and switch-points 44 and 45.

A mounting consisting of two plates 46 of an electrical insulating material, the positions of which are indicated in only partial outline on the enlarged detail Fig. 4, in order to reveal the underlying parts, is pivoted to the member 29 by means of a shaft 47. An integral lug 48, forming one of a pair of anchorages for the compression spring 49, is affixed to the upper portion of the said mounting 46, and the other anchorage is formed by an extension of the guid-

ing screw 31. It will now be clearly evident that the disposition of the mounting plates 46, the pivot 47, and the compression spring 49, is such as to permit a downward thrust to be exerted on the roller members 50, placing it into forceable contact with the commutator 27.

The following cooperating mechanical parts and functions constitute a driving mechanism whereby an intermittent, controlled rotary motion is imparted to the commutator 27. In the enlarged detail, Fig. 4, showing this mechanism, a solenoid 51 is supported in housing 52 and contains a suitable armature 53, the lower end of which has a roller 54 thereon, normally engaging the pivoted plate 55, the said plate being normally held in its upward extending position by virtue of the tension spring 56, the upper end of which is attached to the housing 57 and the lower end to the push-rod 58. The said spring 56 has just sufficient tension to counterbalance the weight of the push-rod 58, the plate 55 and the solenoid armature 53 so that a maximum pressure is obtained between the threaded members 59 and 60 when a suitable current is supplied to the said solenoid 51. The supply and control of this current by suitable switches and contacts will be described more fully hereinafter; the mechanical actions resulting when the current is applied to the solenoid 51 being as follows: The armature 53 having been energized, depresses the plate 55 which in turn engages the push-rod 58 placing the threaded members 59 and 60 into engagement.

The sliding plate 36 which carries with the push-rod housing 57 travels to the left guided by the member 47 (see Fig. 3), and a similar member 60, which engage the slotted portion 61 of the said sliding plate 36. This lateral movement, which is indicated in Fig. 3 by the dotted alternate position A, is transmitted to the slotted lever 62 by means of a wrist-pin 63, the said lever 62 being pivoted near its lower end to the housing plates 46. A ratchet arm 64 having integral ratchet teeth in its lower edge corresponding to a similarly toothed rotary member 65 affixed centrally between the two outer frictional roller sections 50, is pivotally attached to the lever 62. The outer end of the ratchet arm 64 is provided with a grip 66 by means of which it may be raised and lowered, either position being maintained by the action of a toggle-mounted tension spring 67. A connecting link 68 is attached pivotally to the right extremity of the ratchet arm 64 and its opposite end to the pivoted ratchet pawl 69. It will now be apparent that the commutator 27 may be rotated anti-clockwise (Fig. 3) by either of two means, first, by the lateral movement of the sliding arm 36 to the left as applied to the ratchet arm 64, in the down position, and the turning force being applied to the commutator 27 by the friction rollers 50, or secondly, by the same lateral movement of sliding arm 36 as applied to the ratchet pawl 69, the said pawl engaging slots 70 present in the surface of the commutator, when the ratchet arm 64 is in its raised position. The desirability of incorporating both methods in an automatic device of this type arises from the fact that in reconditioning the type of armatures to which this invention relates, that either of two lathe procedures may be required, namely; a deep lathe turning procedure wherein the old slots are completely removed because of deep and uneven wear on the commutator's surface, or secondly, a comparatively shallow turning procedure in which only sufficient metal is removed from the

commutator's surface to true up minor wear, the slots still being in evidence as by the previous slotting operation but requiring going over. In the first instance above referred to, in which the commutator has been turned smooth and flush with its mica insulating sections, my invention provides electrical means of controlling the indexing operation, as follows. In referring to the wiring elements in Fig. 4, it will be noted that a clearly defined electrical circuit exists through the following elements which are wired in series to the source of current L, L, namely, main switch 71 and 72, solenoid 51, contact points 44 and 45, tangential contact brush 26, and peripheral contact brush 19, the said circuit being in continuity when a metal commutator segment as at 73 becomes tangential to both the brush 26 and any portion of the peripheral brush 19. It is now clearly evident that the mechanical rotation elements previously referred to, namely, 36, 62, 63, 64, 67, 68, and 69 are dependent upon the completion of the electrical circuit included by the elements 51, 19, 26, 71, 72, 44, 45, and a commutator bar 73, and can rotate the commutator 27 only a distance B before encountering the following mica section and thus bringing the said rotation to an abrupt stop. The precise point 74 at which this occurs is in exact axial alignment with the path followed by the cutting stroke of slotting-wheel 7, of which more complete details are appended in the section headed "Operating Cycle."

In re-slitting a commutator which has residual slots left in it by a shallow lathe turning procedure, the electrical circuit above described is ineffectual as an indexing means because the insulating medium afforded by the mica segments is absent. It is therefore one of my objects to furnish a simple and convenient means of changing from electrical to mechanical indexing in accordance with the condition of the commutator slots, the method in use being determined by the operator by the position of the lever 64 which, in its downward position, engages the friction roller members 50 to rotate a smoothly turned commutator with the mica flush, the said mica providing the electrical indexing means, or, as in the case of a commutator having residual slots, by raising the said lever 64 to its upward position causing the pawl 69 to engage and rotate the commutator by means of the slots already present on the commutator surface.

The correct alignment, or indexing of the slot by the stated means is accomplished when the pawl 69 has advanced the said slot to position 74 and any further movement beyond this precise point is prevented by the said pawl coming into physical contact with the tangential brush 26 at its recessed portion indicated by the dotted line at 75, the vertical face of which coincides with tangent point 74 of the said brush 26, and also the slotting wheel's path of travel. Since the current supply to the solenoid is incapable of interruption at this phase in the operational cycle of the slotted, because of the absence of the mica insulating segments at the commutator's surface the rotation elements 36, 62, 63, 64, 67, 68 and 69 continue to exert pressure against the pawl and the said pressure increasing until it overcomes the resistance of the compression spring 49 whereupon the housing 46 is forced to the left. Thus the over-travel of the rotation elements are absorbed safely without damage to any of the parts. The inter-related mechanical and electrical parts and functions by which the

disengagement of the pawl is effected prior to a slotting cycle as follows—in Figs. 1 and 2, it is the function, as has been previously explained, of cam 2 to provide primarily, a reciprocating means for the transversely sliding slotting mechanism 8, 9 and 10 and secondarily by virtue of the loosely coupled cam drive 15, 16 and the tension spring 17 to provide a pause interval at the completion of the return stroke in which to allow ample time for the transfer of power from the threaded arbor 6 to the rotation elements 36, 62, 63, 64 and 65 and for the completion of each indexing operation prior to each slotting operation. It has also been provided integrally in the slotter that the pause interval be so timed by the speed of the motor 1, the gear ratio of the worm drive 3, the tension of the return spring 17, the adjustment of the dash-pot 18, and certain frictional considerations, that the expiration of this pause interval occurs coincidentally with the point of maximum over-travel of the lever 62 indicated by the dotted outline C. Fig. 1 shows the relation between contact points 44 and 45 and the position of the sliding carriage elements 8, 9, and 10, which in Fig. 1 are at the extreme right and in Fig. 2 at the extreme left. This arrangement provides the required release of the driving mechanism actuating the pawl 69 at a point just preceding the actual slotting operation, by the movement of the sliding block fitting 9 to the left which releases contacts 44 and 45 and interrupts the solenoid circuit (Fig. 4) permitting the housing 46 to resume its normal position relative to the commutator and the sliding arm 36 to its normal position.

Referring to Fig. 4 the means by which the main switch 71 and 72 is made to shut off automatically with the arm 64 set in its downward position, as in electrically indexing a smoothly turned commutator having flush mica, comprising the edge of arm 64 striking the edge of the movable contact arm 71, when said arm 64 moves upwardly, and deflect it towards the left as shown by dotted position D thus breaking the main current supply circuit when an over-travel of the sliding plate 36 carries the slotted arm to the extreme position C shown. It has already been shown that in the absence of mica at the surface of the commutator that over-travel of the rotation members 36, 62, 63, and 64 must occur. In mechanical indexing this over-travel occurs on every indexing cycle but is prevented from opening the main switch points 71 and 72 by the closure of the shunt switch points 72 and 77 by the arm 64 in its raised position as shown in the 90 degree projected rotation of a section of these parts, Fig. 4. However, the shunt switch 76 and 77 is disengaged at the lower position of the arm 64 and the over-travel occasioned by the failure of the tangential brush 26 to function as a circuit breaker in the absence of the mica, as previously stated, causes the said brush 26 to bridge over the first slot that was cut, after the said slot has made a complete clockwise rotation and thereby holding the solenoid circuit closed until the mechanical elements it has set into motion propel the slotted arm 62 into the extreme position C and deflecting the movable contact arm 71 of the said main switch, thereby stopping the entire operation of the slotter.

It is a further object of the invention to provide means for attachment of the above described mechanisms to any of the lathes commonly used for the turning operation on commutators prior to slotting. It is a prerequisite that the cutting

path of the slotter be in alignment with a vertical projection of the lathe's working center line, the particular method by which this adjustment is made not being a part of this invention; but the preferred embodiment, which is merely a matter of manufacturing expediency, is as follows. The bracket 78 is constructed of such shape and thickness as to bring about the desired alignment between the vertical surface of the back of the lathe's carriage and the lathe's working centers, in accordance with the varying dimensions of the particular lathe to which the slotter is to be fitted. The method by which this bracket 78 is attached is shown in Figs. 2 and 3; the slots 79 accommodate the bolts 80 and secure the said bracket to the end of the lathe carriage by means of holes which are present in most lathe carriages for securing taper attachments to them. In reference to the varying heights between different lathe working centers and their respective carriages, this is compensated for by a vertical adjustment by which the primary mounting members consisting of shafts 11 and 12 of the slotter mechanism are raised and lowered, not only for the above stated purpose, but also to provide a positive and gradual control for the depth of cut by the slotter.

It is also an object of the invention to provide means whereby the slotting device may be folded back so as to permit the lathe to be used unobstructed for other turning operations. A preferred method of accomplishing this is clearly shown in Figs. 2 and 3 wherein a bracket 81 or yoke, shaped as shown in Figs. 1 and 2, surrounds the stationary bracket 78 and is pivoted thereto by a shaft 82, in Fig. 3. An extended portion of bracket 78 provides an anchorage for a pair of grips 83 which terminate in the threaded shafts 84, these engaging similarly threaded holes in the said bracket. The pivoted bracket 81 has slotted extensions 85 (see Fig. 3) in the form of quadrants which are radially concentric with the pivot shaft 82 the threaded shafts 84 previously noted engaging these slots, the adjacent sides of which provide friction surfaces for the tightening of the said grips 83 and thereby providing a holding medium for the slotter in either its vertical operating position, or in its folded position as indicated by the dotted lines at E.

A preferred method for the vertical control of the slotter mechanism is shown in Figs. 1 and 2 in front elevation. The stationary shafts 86 are the two main vertical guide members. These are secured at their lower ends to bracket 81 and held in a parallel position by a cross member 87 at their upper ends, as shown in Figs. 1 and 2. The two horizontal guide shafts 11 and 12 which comprise the main mounting members upon which the slotter mechanism slides are attached at their extremities to two Y-shaped brackets 88 in the manner shown clearly in Fig. 3 and in the dotted extensions of the said shafts in the said bracket in Figs. 1 and 2. The members 89 and 90, which are attached to the yokes as shown in Figs. 1 and 2 are slideably attached to the vertical guide members 86 by suitable holes in them. The sliding member 89 is provided with a threaded hole at its center which is engaged by a similarly threaded shaft 91, the upper portion of which is rotatably mounted by set collars 92 in the member 87, and has a rotation handle 93 affixed to its upper extremity by which the said shaft can be revolved and the cooperating vertically sliding members 88, 89 and 90, and the

attached horizontal guide shafts 11 and 12 can be raised and lowered.

Operating cycle

The following describes one complete cycle of the operation of the slotting device. The slotted is attached to and aligned with the lathe for which it has been adapted as previously described and the commutator of an armature of the type previously indicated has been turned in the said lathe so that its radially disposed mica segments are flush with the commutator's peripheral surface, the said armature then being left in the lathe as in turning. The driving means for the lathe headstock is then disengaged. Figs. 1 and 2 show the slotted longitudinally aligned by means of the lathe's carriage control so that the left peripheral contact brush 19 aligns with the outer edge of the commutator's annular extended rim 20 and the right hand roller of member 50 aligned by means of the regulating member 38 so that its right hand edge coincides with that of the commutator. The slotted mechanism is then lowered by means of the vertical regulative screw and handle 91 and 93 thereby placing the rollers into forceable contact with the commutator's 27 periphery, the vertical adjustment being completed when the required depth of cut is obtained by visual alignment between the bottom of the slotted wheel 7 and the surface of the commutator. It is assumed that the slotted carriage assembly 8, 9, and 10 is at its extreme right position where it would normally rest after the completion of a previous slotting operation and that the driving pin 15 and arm 16 are not making contact which would also be the case normally. The armature is then positioned radially so that the tangential brush 26 is making contact with one of the commutator's metallic segments (Fig. 4). Next the ratchet arm 64 is placed in its "down" position (see Fig. 4) and the switch handle 66 to its "on" position, thereby starting the motor 1 and rotating the cutting spindle 6. Contact points 44 and 45 are closed at this point in the cycle as shown in Fig. 1, and a complete electrical circuit exists between the elements 51, 19, 26, 71, 72, 44 and 45 by which the solenoid, acting upon the mechanical elements 36, 62, 63, 64, 68, 69, and 50 is enabled to effect rotation of the armature. The rotation thereby effected is under considerable frictional restraint occasioned by the parts of the lathe which necessarily rotate with the armature and of the parts in control of the armature's positioning such as the tail stock center 94 or a chuck. These combined frictional sources together with that of the peripheral brush 19 which is under spring-tensioned engagement with the rim 20 of the commutator 27 as previously explained act as a brake by which the relatively small amount of momentum acquired by the revolving armature is instantly checked when the electric current which activates the said rotary movement is interrupted by the interposition of a mica segment. At the conclusion of this rotary movement and the subsequent abrupt cessation thereto the position of the mica is correct for the slotting operation, it being in coincidence with the tangential point of the brush 26 and the slotted's cutting wheel 7 path of travel as shown in Fig. 4, the said path of travel being in precise alignment with the said tangential point of the brush 26 and the mica segment. At this point the cam driving arm 16, actuated by the worm drive 3 has caught up with the drive pin 75

15 on the cam wheel 2 and started the sliding carriage 8 with the attached slotting mechanism to the left, opening contacts 44 and 45. The vertically slideable arm 28 with its attached tangential brush 26 is raised by the cam 34 at the proper instant to allow cutter shaft 6 and wheel 7 to pass under it. The sliding carriage 8 can travel to the left only as far as the diameter of the cam disk 2 permits a thrust in that direction, and the position of the member 25 is always stationary in respect to that limiting point; hence, this member serves as a guide for the left limit of the cutting stroke. The cutter mechanism having performed its function and slotted the mica now starts its return stroke in the groove it previously cut and the cam 34 raises the contact arm 28 and its attached brush 26 as previously noted. The carriage 8 is not power impelled on this return stroke but is drawn to the right by the spring 17 as the cam 2 passes dead center, this being possible by virtue of the loose coupling existing between the cam-shaft 14 and cam 2, said coupling consisting of the fixed pin 15 attached to the face of the cam disk 2, which is free to disengage the cam driving arm 16 at the position indicated in Fig. 2; an alternate subsequent position being shown in Fig. 1 wherein the carriage has completed its movement to the right.

30 At the completion of the final slotting operation and with the resumption of electrical contact between the tangential brush 26 and the metallic surface of the commutator, the rotation of the commutator proceeds as previously stated, 35 but in the absence of the peripheral flush mica heretofore functioning as an interrupting medium, the tangential brush 26 merely by-passes and bridges over the interstice from which the mica was removed by the initial slotting operation and thereby compels the said brush to electrically engage and contact two consecutive metallic commutator segments. Thus a prolonged 40 interval of activation is maintained in the solenoid, which persists until the cooperating mechanical elements have reached their extreme 45 limit as shown in Fig. 4, in which the position C of the slotted lever 62 has contacted and deflected the moveable point and arm 71 of the main switch 71 and 72 thus shutting off the main power supply to the entire slotted mechanism.

50 The operation of the slotted on a commutator having residual slots as by a previous slotting operation, in the case wherein a shallow lathe turning procedure has left such slots in evidence and which are required to be re-slotted to their proper depth and to be cleanly re-slotted because of burring tendencies of the copper bars over the slotted interstices, is essentially the same as described before, with the exception that the ratchet arm 64 is raised to its "up" position at the beginning of the actual slotting process, and the mechanism must be shut-off manually using the same lever 64 in its lowered position.

55 While I have described the preferred embodiment of my invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

60 What I claim is:

65 1. In a machine of the class described, the combination of a movable support, said support

provided with a pair of fittings, a carriage slidably mounted on said fittings, a motor on said support, a milling device depending from said carriage under said fittings, means connecting said motor and milling device for operating said milling device when said carriage moves in one direction, means for automatically returning said carriage to a set position, indexing means on said support, means electrically connecting said indexing means to said motor, a housing and means supporting said housing upon said carriage, said housing provided with a push rod, said push rod being adapted to engage said milling device, a sliding plate fixedly secured to said housing, a slotted plate provided at its lower end with a pawl, means connecting said motor and said milling device, and means electrically connecting said motor and said slotted plate, whereby when the milling device has completed a cycle of operation, said pawl will be operated to move a commutator.

2. A supporting frame including laterally spaced, vertical side members, a secondary frame slidably mounted on said side members, said secondary frame including spaced side members and guide rods connecting the side members of the secondary frame, a bed slidably mounted on said guide rods, a motor mounted on said bed, a cam shaft driven from said motor, a cam rotatably mounted on said cam shaft, a fixed member carried by the secondary frame and having said cam engaging therewith, a cam operating arm fixed to said cam shaft, a pin projecting laterally from said cam for engagement by said arm during one arc of rotation of the cam and disengaging from the arm during the remaining arc of rotation of said cam, a tension spring having one end fixed to said fixed member and holding said cam in contact therewith, a hanger depending from said bed, a bearing at the lower end of the hanger, an arbor journalled in said bearing and carrying an armature slitting mill, means driven by the motor for driving said arbor, and means to support a commutator rotatably in the path of said mill.

3. A supporting frame including laterally spaced, vertical side members, a secondary frame slidably mounted on said side members, said secondary frame including spaced side members and guide rods connecting the side members of the secondary frame, a bed slidably mounted on said guide rods, a motor mounted on said bed, a cam shaft driven from said motor, a cam rotatably mounted on said cam shaft, a fixed member carried by the secondary frame and having said cam engaging therewith, a cam operating arm fixed to said cam shaft, a pin projecting laterally from said cam for engagement by said arm during one arc of rotation of the cam and disengaging from the arm during the remaining arc of rotation of said cam, a tension spring having one end fixed to said fixed member and holding said cam in contact therewith, a hanger depending from said bed, a bearing at the lower end of the hanger, an arbor journalled in said bearing and carrying an armature slitting mill, means driven by the motor for driving said arbor, means to support a commutator rotatably in the path of said mill, and means operating by reciprocation of said bed and effecting step-by-step rotation of the commutator.

4. A supporting frame including laterally spaced, vertical side members, a secondary frame slidably mounted on said side members, said secondary frame including spaced side members

- and guide rods connecting the side members of the secondary frame, a bed slidably mounted on said guide rods, a motor mounted on said bed, a cam shaft driven from said motor, a cam rotatably mounted on said cam shaft, a fixed member carried by the secondary frame and having said cam engaging therewith, a cam operating arm fixed to said cam shaft, a pin projecting laterally from said cam for engagement by said arm during one arc of rotation of the cam and disengaging from the arm during the remaining arc of rotation of said cam, a tension spring having one end fixed to said fixed member and holding said cam in contact therewith, a hanger depending from said bed, a bearing at the lower end of the hanger, an arbor journalled in said bearing and carrying an armature slitting mill, means driven by the motor for driving said arbor, means to support a commutator rotatably in the path of said mill, and means operating by reciprocation of said bed and effecting step-by-step rotation of the commutator, said last means including an electric circuit controlled mechanism having a circuit closing contact movable into and out of engagement with the commutator and camming means on the bed controlling the movement of the circuit-closer from the commutator.
5. A supporting frame including laterally spaced, vertical side members, a secondary frame slidably mounted on said side members, said secondary frame including spaced side members and guide rods connecting the side members of the secondary frame, a bed slidably mounted on said guide rods, a motor mounted on said bed, a cam shaft driven from said motor, a cam rotatably mounted on said cam shaft, a fixed member carried by the secondary frame and having said cam engaging therewith, a cam operating arm fixed to said cam shaft, a pin projecting laterally from said cam for engagement by said arm during one arc of rotation of the cam and disengaging from the arm during the remaining arc of rotation of said cam, a tension spring having one end fixed to said fixed member and holding said cam in contact therewith, a hanger depending from said bed, a bearing at the lower end of the hanger, an arbor journalled in said bearing and carrying an armature slitting mill, means driven by the motor for driving said arbor, means to support a commutator rotatably in the path of said mill, and means operating by reciprocation of said bed and effecting step-by-step rotation of the commutator, said last means including an electric circuit controlled mechanism having a circuit closing contact movable into and out of engagement with the commutator and camming means on the bed controlling the movement of the circuit-closer from the commutator.
6. A supporting frame including laterally spaced, vertical side members, a secondary frame slidably mounted on said side members, said secondary frame including spaced side members and guide rods connecting the side members of the secondary frame, a bed slidably mounted on said guide rods, a motor mounted on said bed, a quick return mechanism driven by said motor and reciprocating said bed between the side members of the secondary frame, a hanger depending from said bed, a bearing at the lower end of the hanger, an arbor journalled in said bearing and carrying an armature slitting mill, means driven by the motor for driving said arbor, and means to support a commutator rotatably in the path of said mill.
7. A supporting frame including laterally

spaced; vertical side members, a secondary frame slidably mounted on said side members, said secondary frame including spaced side members and guide rods connecting the side members of the secondary frame, a bed slidably mounted on said guide rods, a motor mounted on said bed, a quick return mechanism driven by said motor and reciprocating said bed between the side members of the secondary frame, a hanger depending from said bed, a bearing at the lower end of the hanger, an arbor journaled in said bearing and carrying an armature slitting mill, means driven by the motor for driving said arbor, means to support a commutator rotatably in the path of said mill, and means operating by reciprocation of said bed and effecting step-by-step rotation of the commutator.

8. A supporting frame including laterally spaced, vertical side members, a secondary frame slidably mounted on said side members, said secondary frame including spaced side members and guide rods connecting the side members of the secondary frame, a bed slidably mounted on said guide rods, a motor mounted on said bed, a quick return mechanism driven by said motor and reciprocating said bed between the side members of the secondary frame, a hanger depending from said bed, a bearing at the lower end of the hanger, an arbor journaled in said bearing and carrying an armature slitting mill, means driven by the motor for driving said arbor, means to support a commutator rotatably in the path of said mill, and means operating by reciprocation of said bed and effecting step-by-step rotation of the commutator, said last means including an electric circuit closing contact movable into and out of engagement with the commutator and camming means on the bed controlling the movement of the circuit closer from the commutator.

9. A supporting frame including laterally

spaced, vertical side members, a secondary frame slidably mounted on said side members, said secondary frame including spaced side members and guide rods connecting the side members of the secondary frame, a bed slidably mounted on said guide rods, a motor mounted on said bed, a quick return mechanism driven by said motor and reciprocating said bed between the side members of the secondary frame, a hanger depending from said bed, a bearing at the lower end of the hanger, an arbor journaled in said bearing and carrying an armature slitting mill, means driven by the motor for driving said arbor, means to support a commutator rotatably in the path of said mill, means operating by reciprocation of said bed and effecting step-by-step rotation of the commutator, and means including an electrically operated mechanism for rotating the armature, other manually operable mechanism for rotating said armature, and means for effecting selective operation of said last two mechanisms.

IRVING SPECTOR.
